UNITED STATES PATENT OFFICE.

EDWARD J. YETTER, OF DENVER, COLORADO.

EXPANSION-JOINT STRIP.

Application filed October 31, 1921. Serial No. 511,850.

To all whom it may concern:

Be it known that I, EDWARD J. YETTER, a citizen of the United States of America, residing at the city and county of Denver and 5 State of Colorado, have invented new and useful Expansion-Joint Strips, of which the following is a specification.

This invention relates to expansion joint strips, i. e., strips of material commonly 10 placed between adjoining slabs of concrete or the like to allow for contraction and expansion thereof.

The more specific object of the invention is the provision of a strip of the type referred to, which is better adapted for practical use than expansion strips heretofore used.

Expansion joint strips heretofore made generally had as outside layers felt saturated 20 with a water-resisting material, usually asphalt or other bituminous material. The sole function of these layers of felt was to maintain the expansion material proper in place and to lend stiffness to the strips 25 for purposes of handling as well as for positioning in place during the formation of the joints.

In contradistinction to this practice, the present invention comprises a layer of water- 30 proof, adhesive material, preferably of the expansive compound, on one or both sides of the strip.

In the drawings, Figs. 1-4 represent cross-sections of various forms of strips embodying the invention.

In common with the usual practice, the expansion joint strips of the invention essentially include a body A of asphalt compound which may be applied as a single 40 relatively heavy layer or in a plurality of layers. Furthermore, in common with the usual practice I employ layers of felt saturated with a waterproofing solution.

In Fig. 2 the expansive compound, or asphalt compound in particular, is contained between two layers of saturated felt or raw waterproofed felt B. The arrangement thus far described corresponds substantially to usual constructions heretofore applied in 50 practice. In accordance with the more specific object of the invention, however, I provide the outside surfaces of the felt with layers C of an adhesive waterproof material which, generally, may be asphalt compound. 55 These layers are of considerable practical

importance inasmuch as they provide a binder between the body of the strip and the adjoining face of the block or slab. As the successive blocks or slabs are formed, they press the strip firmly against the finished block and under this pressure the compound of the outside layers enters the pores of the material thereof and effectively bonds the strip to the adjoining blocks. This bonding action is augmented in course of time when the blocks expand under the influence of heat.

In order to prevent the strips from sticking together I provide the surfaces of the outside layers C with a thin coating D of ground mica or talc or any other finely divided or comminuted non-adhesive material. The strips may thus be readily shipped and handled just like the strips heretofore used.

While the construction just described serves best the purposes of the invention, in some cases only one outside surface C of adhesive compound is sufficient. The construction shown in Fig. 1 is essentially like that shown in Fig. 2, but a layer D of adhesive compound is provided only on one of the layers B of felt.

The construction illustrated in Fig. 3 consists of only one layer B of felt to which are applied, on opposite sides, layers A₁ and A₂ of the compound. While this form of construction necessarily cannot have the same range of compression and expansion movement which is limited more or less to that of the felt, it emphasizes the importance of bonding the strip to the faces of the adjoining blocks.

The construction in Fig. 4 consists of two layers A₃ and A₄ of compound on opposite sides of a sheet E of burlap and two layers C of felt on the outside. On the outside surface of one of the layers of felt is provided a layer D of the adhesive compound.

In the foregoing I have described various forms of the invention. It is understood, however, that the strip proper may assume many forms, such as at present in use or as may be developed. The essential point is the provision of a layer of waterproof adhesive material on one or both outside surfaces of the strip for forming a bond between the latter and the adjoining blocks or slabs.

While I have made reference only to blocks or slabs, I have done so merely as a

matter of convenience. The invention, as is obvious, is applicable to all cases in which expansion strips are or can be used.

Having described my invention, what I claim as new, and desire to secure by Letters Patent, is:

1. An expansion joint strip comprising a layer of impregnated felt, a relatively thick layer of asphaltic material upon one side 10 of said felt, a relatively thin layer of asphaltic material upon the opposite side of said felt, a second layer of impregnated felt contacting with said thicker layer of asphaltic material, and a coating of finely 15 divided non-adhesive material on the outer face of said thin layer of asphaltic material.

2. An expansion joint strip comprising two layers of impregnated fabric, a relatively thick layer of asphaltic material between the said layers of fabric, a relatively thin 25 layer of asphaltic material upon the outer surfaces of the layers of fabric and a coating of finely divided non-adhesive material on each of said thin layers.

3. An expansion joint strip including a 30 layer of felt having on one side a thick layer of asphaltic material and on the other side a thin layer of waterproof adhesive material, and a coating of finely divided non-adhesive material covering the thin layer. 35

In testimony whereof I affix my signature.

EDWARD J. YETTER.
